UNITED STATES PATENT OFFICE.

LOUIS LAWRENCE, OF DALLAS, TEXAS.

COMPOSITION OF MATTER FOR IMPROVING THE TONE OF A VIOLIN.

No. 856,533.

Specification of Letters Patent.

Patented June 11, 1897.

Application filed September 22, 1906. Serial No. 336,839.

To all whom it may concern:

Be it known that I, LOUIS LAWRENCE, a citizen of the United States, residing at Dallas, in the county of Dallas and State of Texas, have invented a new and useful Composition of Matter for Improving the Tone of a Violin and All other String Musical Instruments, of which the following is a specification.

My composition consists of the following ingredients combined in the proportions stated, namely:—alcohol (absolute) 1 gallon, gum of guaiac 1 pound, peel of three oranges, ether (sulfuric purified) 2 ounces. These ingredients are to be thoroughly mingled by agitation. The above named composition to be applied to the inside of the back of the instrument. The instrument is then placed on its back, and allowed to remain for fifteen or twenty minutes. It is then ready for use.

By the use of the above composition, the tone of the violin or other string musical instrument is speedily, thoroughly and permanently improved, said composition having the effect of graduating and equalizing the tone, softening and purifying the same and making the same more musical, and eradicates the woody tone common to all string musical instruments.

By the use of the above composition, and by reason of the improved quality of the tone and sound of the strings, the instrument

is thereby rendered less difficult to finger, requiring less labor for the operator, and increases the tone of the various strings, and the volume of sound produced by the instrument. One application of the above composition is permanent in its effect and the composition is non-injurious to either strings or other parts of the instrument. By the application of the above composition the instrument is prematurely aged.

Applicant desires to reserve the right to vary the proportions of the ingredients in the above named composition as far as consistent with the rules of this Office.

I claim:

1. The hereinabove described composition of matter, consisting of alcohol (absolute) 1 gallon; gum of guaiac, 1 pound; peel of three oranges, and; ether (sulfuric purified) 2 ounces, substantially as described and for the purposes specified.

2. A composition for improving the tone of violins and other stringed instruments consisting of alcohol, gum of guaiac, orange peel, and ether.

In testimony whereof I have signed my name to this specification in the presence of two subscribing witnesses.

LOUIS LAWRENCE.

Witnesses:

JOHN M. SPELMAN,
CORA LAWRENCE.
